UNITED STATES PATENT OFFICE.

FELIX D. LANGEVIN, OF LOWELL, MASSACHUSETTS, ASSIGNOR TO SACO-LOWELL SHOPS, OF BOSTON, MASSACHUSETTS, A CORPORATION OF MASSACHUSETTS.

GRID FOR PICKERS, OPENERS, AND ALLIED MACHINES.

1,182,575.

Specification of Letters Patent.

Patented May 9, 1916.

Application filed September 7, 1915. Serial No. 49,197.

To all whom it may concern:

Be it known that I, FELIX D. LANGEVIN, of Lowell, in the county of Middlesex and State of Massachusetts, a citizen of the United States, have invented a new and useful Improvement in Grids for Pickers, Openers, and Allied Machines, of which the following is a full, clear, and exact description, reference being had to the accompanying drawings, forming a part of this specification, in explaining its nature.

The present invention relates to an improvement in grid for pickers, openers and allied machines.

15 The essential idea residing in the invention is a grid having bars which are adjustable for varying the opening between them and in which the working edge of the bars maintains a constant position with relation 20 to the path of the beater or other working part, whatever the adjusted position of the bars may be, the object being to improve the efficiency of the machine.

The invention can best be seen and understood by reference to the drawings in which—

Figure 1 is a side elevation of a grid embodying my invention, and Fig. 2 is also a side elevation of the grid with the bars 30 thereof shown in a different adjusted position from that shown in Fig. 1.

1 represents the curved side or cheek which supports the ends of the bars at one side of the grid, the other side or cheek (not 35 shown) supporting the opposite ends of the bars, being an exact duplicate. The sides are adjustably secured to the frame of the machine in the usual manner.

2 represents the bars the ends of which 40 rest within sockets 3 formed in the side pieces. The bars are held within the sockets by means of a capping strap 4 which extends over the open ends of the sockets, closing them, and is secured to the side 45 piece.

5 represents the beater.

In the drawings some of the bars are shown as fixed bars. Inasmuch as the present invention pertains only to the adjustable bars, the following description will pertain only to these bars, or, in other words, to the mounting and control thereof. The sockets containing the ends of the adjustable bars have each a generally rectangular form, 55 6 and 7 indicating respectively the opposite

sides of each of these sockets, and 8 the bottom of the socket. The open ends of the sockets are closed by the capping strap as aforesaid.

The bars themselves are made to have a 60 generally triangular cross section, the broadened or base portion of the bar being snugly contained between the two sides of the socket adjacent the capping strap with the face 10 of the bar bearing against this 65 strap substantially as shown in Fig. 2, that is, when the bars are occupying their normal position.

11 represents the working edges of the bars, and it will be observed that these edges 70 lie within the angles formed by the capping strap 4 and the sides 6 of the sockets.

12 represents the opposite corner edges of the bars. These edges lie normally within the angles formed by the capping strap and 75 the sides 7 of the sockets.

14 and 15 represent, respectively, the opposite converging sides of the bar which project down into the socket, and 16 the end which lies adjacent the bottom of the 80 socket but so far removed therefrom and from the sides of the socket as will permit of the bars being moved freely.

With the bars thus socketed and arranged, the faces 10 thereof and consequently the 85 working edges of the bars lying within a common curved plane, will occupy such proper position relatively to the path of the beater as will depend upon the adjusted position of the side pieces or cheeks (see Fig. 2). The bars will also occupy a minimum spaced relationship to each other, the space between the bars being determined by the distance between the working edge 11 of one bar and the adjacent edge 12 of the 90 bar next to it. The object is to now increase the spaced distance between the bars without changing the position of the working edges of the bars with relation to the path of the beater, or, in other words, changing 95 that position of the working edges of the bars with relation to the path of the beater which has been initially obtained by adjustment of the sides or cheek pieces. This effect is obtained by turning the bars within 100 their sockets, each around its working edge as a center, when the faces 10 of the respective bars will draw out of the normal curved path in which they were initially disposed and occupy positions parallel to 110

one another as shown in Fig. 1. In attaining such positions the edge 12 of each adjacent bar will draw downwardly away from the working edge of the bar next to it, thereby increasing the distance between the bars but without changing the position of the working edges of the bars with relation to the path of the beater. The parts are turned within their sockets by an application of force to the bottom ends of the bars, the bars being held during such turning to pivot around their working edges by the capping strap 4 and side 6 of the socket against which the working edges of the bars have bearing.

The adjustable bars are simultaneously adjusted and afterward held securely in their adjusted positions by means of dogs 18 secured to the side pieces. In other words, two dogs are employed, one secured to each side piece, of which but one is shown, the other being an exact duplicate as before explained. The dog 18 has a toothed edge facing the adjustable bars and is arranged whereby the ends 16 of the bars will project into the openings 19 between the teeth. The dog is secured to the side piece by means of a bolt 20 which passes through a slot 21 in the dog. The movable retention 30 of the dog is further obtained by means of pins 22 projecting from the side pieces and entering slots 23 in the dog on either side of the bolt connection. The slots 21 and 23 permit of the dog being moved backward 35 and forward for performing the adjustment of the bars, after which the dog and bars held by it are fixed in their adjusted position by the tightening of the bolt connection. It should be further explained that the slots 40 21 and 23 are so formed in the dog that as the dog is moved back and forth for adjustably moving the bars it will have such movement as will permit of the bars being turned by the dog around their working 45 edges, the dog adapting itself to the changed position of the bars with a further capability of fixture in any position to which it may be moved within the range of adjustment of the bars.

Having thus fully described my invention, I claim and desire to secure by Letters Patent of the United States:—

1. A grid for pickers, openers and allied machines comprising a series of spaced grid bars adjustable for varying the amount of space between said bars, each of said bars presenting a working edge, and means whereby the working edges of said bars may be held to maintain a constant position during the adjustment thereof.

2. A grid for pickers, openers and allied machines having a series of spaced adjustable bars, each presenting a working edge, and means for controlling and otherwise effecting the adjustment of said bars for

varying the spaced relationship thereof without changing the positions of the working edges thereof.

3. A grid for pickers, openers and allied machines having side pieces and a series of spaced grid bars mounted thereon and adjustable for varying the distance between said bars, each of said bars presenting a working edge, and means for controlling said bars and otherwise effecting the adjustment thereof for varying the space between the same as aforesaid and at the same time maintaining the working edges thereof in a constant position.

4. A grid for pickers, openers and allied machines having side pieces and a series of spaced grid bars mounted to turn upon said side pieces for varying the distance between said bars, each of said bars presenting a working edge and being otherwise formed, arranged and maintained whereby the bars may be turned within said side pieces for varying the spaced distance between the same without changing the position of the working edges of said bars.

5. A grid for pickers, openers and allied machines comprising a series of spaced bars adjustable for varying the distance between said bars, each of said bars having a face presenting a working edge, and means whereby the relative positions of the faces of said bars may be changed for effecting the spaced adjustment thereof without changing the position of the working edges of said bars.

6. A grid for pickers, openers and allied machines comprising a series of spaced bars adjustable for varying the distance between said bars, each of said bars having a face presenting a working edge, and means for supporting and otherwise controlling said bars whereby the faces of the bars may be turned around their working edges for obtaining the spaced adjustment of said bars.

7. A grid for pickers, openers and allied machines having side pieces and a series of spaced grid bars mounted to turn within said side pieces for varying the spacing between said bars, each of said bars having a face presenting a working edge, and means for controlling and otherwise retaining said bars whereby they may be turned within said side pieces for effecting the spaced adjustment thereof and the faces of said bars turned around the working edges of said bars.

8. A grid for pickers, openers and allied machines having side pieces and a series of spaced grid bars mounted to turn within said side pieces for varying the spacing between said bars, each of said bars having a face presenting a working edge, and means for controlling and otherwise retaining said bars whereby upon the turning thereof within said side pieces the working edges

- of said bars may be maintained in a constant position and the face of each of said bars of the series turn toward or away from the working edge of the next adjacent bar.
5. A grid for pickers, openers and allied machines having side pieces and a series of spaced grid bars mounted to turn thereon for varying the spaced relationship of said bars, said bars being substantially triangular in cross section and having a face presenting a working edge, and means for controlling and otherwise maintaining said bars whereby they may be turned within said side pieces and each of said bars be turned
- 10 around its working edge for varying the positions of the faces of said bars with relation to the working edges of successive bars.
10. A grid for pickers, openers and allied machines having side pieces and a series 20 of spaced grid bars mounted to turn thereon for varying the spaced relationship of said bars, said bars being substantially triangular in cross section with converging sides and a face presenting a working edge, 25 means for retaining said bars within said side pieces whereby they may be turned for effecting the spaced adjustment thereof, each around its working edge, and a dog assisting in the retention of said bars and 30 movable for effecting a simultaneous adjustment thereof substantially as described.
